DIE FOR MAKING INTERLOCKING BRICKS

Roy Morrelle Bender, La Canada, Calif.

Application April 8, 1940, Serial No. 328,515

1 Claim. (Cl. 25—102)

This invention relates to brick making and more especially to a machine for making interlocking brick.

An object of the invention is to provide an improved machine construction for making interlocking brick.

Another object is to provide in a brick and block repress machine improved reciprocating dies for forming interlocking brick.

More particular objects and advantages will appear and be brought out more fully in the following specification, reference being had to the accompanying drawings, wherein:

Fig. 1 is an elevation view partly in section of a brick and block repress machine embodying my invention;

Fig. 2 is a sectional view taken along the line 2—2 of Fig. 1;

Fig. 3 is a perspective view of the upper reciprocating die element;

Fig. 4 is a perspective view of one of the lower die elements;

Fig. 5 is a perspective view of a second lower die element;

Fig. 6 is a plane view of a portion of the feeding table showing the brick in the reforming position;

Fig. 7 is a sectional view taken along the line 7—7 of Fig. 6; and

Fig. 8 is a perspective view of a typical brick made by the machine; Fig. 9 is a perspective view showing the upper die element heating member.

Referring more particularly to the drawings, I show a machine frame 10 having a feeding table frame 11 which supports a brick feeding table 12 having an aperture therein through which extends a portion of frame 11. Frame 11 is adapted to form a pair of substantially rectangular apertures 13 which serve as guides for the vertically reciprocable die members 14, 15 and 16. Frame 10 has bearings 17 for a rotary shaft 18 on which is mounted a substantially elliptical cam 19 of suitable shape.

A pair of guide members 20 are suitably secured to frame 10 and a reciprocable die support 21 is mounted therebetween and provided with a roller 22 which rides on cam 19 and is raised thereby upon rotation of the same on shaft 18. A pair of die members 16 are suitably secured on support 21 and are adapted to be raised and lowered through apertures 13 as support 21 is raised and lowered. Dies 16 are substantially rectangular in shape and each has a vertical longitudinal slot 23 and a pair of transverse vertical slots 24. A plurality of top plates 25 are ad-

justably mounted as by screws or otherwise to the top portions of die members 16 so as to permit exact sizing of the molded brick.

Die member 15 comprises a web portion 26 and a plurality of web portions 27 transverse thereto, web portion 26 having a pair of feet 28 each having a threaded bore 29 for mounting on a stud bolt 30 which is provided with an adjustable lock nut 31. The heads of bolts 30 rest on frame 10 at the lower position of the die stroke; die member 15 is adapted to interfit with die member 16, web portion 26 being positioned in slot 23 and web portions 27 in slots 24, the base portion 23a of slot 23 being adapted to engage the lower side of web 26 for raising die member 15 during the upstroke for removal of the brick.

Die members 14 are each suitably secured as by bolts 32 to a reciprocating block 33 which is actuated and synchronized with the movement of die members 16 and 26 so as to be lowered when the latter are raised and be raised when the latter are lowered by conventional mechanism which is not shown.

A heating element 34 is secured to the lower face of die member 14 and a die plate 35 is secured to heating element 34. Die member 35 has a longitudinal groove 36 and a pair of transverse grooves 37 adapted to correspond to web portions 26 and 27 and are formed with sloping wall portions as shown.

The operation of the invention should be clear from the foregoing description. The wet bricks of rectangular shape are fed from table 12 onto plates 25 of die member 16 and the top edges of webs 26 and 27 of die member 15 which are at this moment level with plates 25, cam 19 being in the upper position. At this moment die member 14 will be raised to permit the placing of the brick as described.

Upon the rotation of shaft 18 a half turn cam 19 will be carried to the lower position as seen in Figs. 1 and 2, and die members 15 and 16 will be dropped, carrying the brick into apertures 13. Die member 15 will be held by bolts 30 on frame 10 while die member 16 drops below it at a distance equal to the depth of grooves 36 and 37, and die 14 will be carried down by the synchronizing mechanism forming the interlocking grooves and beads A and B, respectively, on the brick as shown in Fig. 8.

Upon the further half turn of shaft 18 which raises cam 19, die member 16 will be raised, and it in turn will pick up and raise die member 15 and raise the brick to table level, it being un-

derstood that the die member 14 will have been raised previously so that the finished brick may be removed and replaced with a new wet brick.

Heating element 34 will serve to free die plate member 35 from the beads B of the brick.

Having described my invention, what I claim is:

In a brick and block repress as described, having a table provided with a walled aperture, an upper die member having a bead forming groove and a pair of lower die members mounted for reciprocation in said aperture, one of said lower die members having a plate portion and a plu-

5 rality of vertical slots, the second of said lower die members having web portions extending substantially across said aperture, adapted for reciprocation in said slots, abutment supporting means for said second lower die member, said first lower die member having means to engage and raise said second die member with said first die member to said table, said first lower die member adapted to be lowered farther than said second lower die member whereby to form a groove in the bottom and a bead on the top of the brick when the upper die member is lowered.

ROY MORRELLE BENDER.
